(57) **CLAIM**

The ornamental design for a display package, as shown and described.

DESCRIPTION

The patent or application file contains at least one drawing executed in color. Copies of this patent or patent application publication with color drawing(s) will be provided by the Office upon request and payment of the necessary fee.

FIG. 1 is a color front perspective view of a display package showing my new design.

FIG. 2 is a color right side perspective view thereof.

FIG. 3 is a color left side perspective view thereof.

FIG. 4 is a color bottom perspective view thereof.

FIG. 5 is a color top perspective view thereof.

FIG. 6 is a color rear perspective view thereof.

FIG. 7 is a color second rear perspective view thereof; and, FIG. 8 is a color front exploded perspective view thereof, with the display tube removed, and the top of the package open for clarity of illustration.

1 Claim, 5 Drawing Sheets
